UNITED STATES PATENT OFFICE

94,424

DESIGN FOR A COMBINED CIGARETTE RECEPTACLE AND MATCH HOLDER

Evelyn Jahncke, New Orleans, La.

Application February 5, 1934, Serial No. 50,610

Term of patent 3½ years

To all whom it may concern:

Be it known that I, Evelyn Jahncke, a citizen of the United States, residing at New Orleans, in the parish of Orleans and State of Louisiana, have invented a new, original, and ornamental Design for a Combined Cigarette Receptacle and Match Holder, of which the following is a specification, reference being had to the accompanying drawing, forming a part thereof.

In the drawing

Figure 1 is a plan view of the combined cigarette receptacle and match holder showing my new design; and

Figure 2 is a side elevational view thereof.

The design is made in fanciful simulation of an aeroplane body provided with an open receptacle in its top to receive cigarettes, while slotted openings are provided in opposite sides of the body for holding match books in a manner suggestive of the wings of an aeroplane.

I claim:

The ornamental design for a combined cigarette receptacle and match holder, substantially as shown and described.

EVELYN JAHNCKE.
